UNITED STATES PATENT OFFICE.

ZENAS P. CANDEE, OF WATERBURY, CONNECTICUT, ASSIGNOR TO THE WATERBURY-FARREL FOUNDRY AND MACHINE COMPANY, OF WATERBURY, CONNECTICUT, A CORPORATION OF CONNECTICUT.

STAMPING-PRESS.

1,354,377.

Specification of Letters Patent. Patented Sept. 28, 1920.

Application filed May 1, 1919. Serial No. 294,124.

To all whom it may concern:

Be it known that I, ZENAS P. CANDEE, a citizen of the United States, residing at Waterbury, in the county of New Haven and State of Connecticut, have invented certain new and useful Improvements in Stamping-Presses, of which the following is a specification, reference being had therein to the accompanying drawings.

10 My invention relates to a new and improved stamping press, having more particular reference to that type of press wherein the gate is operated through the action of the screw.

15 It is the object of this invention, among other things, to automatically actuate the screw of a press of this character and thus obviate the necessity of manipulating the same manually as heretofore, and further,

20 to so operate the same that the pressure exerted by the tools upon the work during successive operations will be uniform, a result that is impossible of attainment with manually operated presses, another object being,

25 to so design a press having these desirable features, that the mechanism will not be complicated but simple in both design and structure and easily and economically constructed and assembled.

30 To these, and other ends, my invention consists in the new and improved stamping press having certain details of construction and combinations of parts as will be herein-after described and more particularly pointed out in the claims.

Referring to the drawings, in which like numerals of reference designate like parts in the several figures:

Figure 1 is a front elevation of my improved press;

Fig. 2 is a side elevation thereof, partly in section;

Fig. 3 is an enlarged plan view showing the relative position of some of the parts when the gate is in its down position;

Fig. 4 is a similar view with the gate in its up position;

Fig. 5 is a sectional view of the spring adjusting means, taken upon line 5—5 of Fig. 4;

Fig. 6 is a fragmentary plan view of the clamp arm and adjacent mechanism;

Fig. 7 is a sectional view of the parts shown in Fig. 6, taken upon line 7—7 thereof;

Fig. 8 is an enlarged plan view of the friction mechanism; and

Fig. 9 is a sectional view of the crank pin and adjacent parts, taken upon line 9—9 of Fig. 3.

Heretofore screw presses have generally been operated manually, the operator grasping a handle or lever fixed to the upper portion of the screw and by rotation thereof the gate is caused to move toward the bed of the press and any work therebetween is acted upon by the dies, one of which is fixed in the bed and the other in the gate. This method of operation is, of course, costly, in that it requires an operator for each machine, and the pressure upon the work varies with the strength and activity of the operator so that two presses of exactly the same structure, operated by different persons will produce entirely different results on certain classes of work. This latter is especially true with work produced from thin metal, such as is required in the jewelry, optical and novelty trades.

Experience has demonstrated that not only does the character of the work produced vary between exactly similar machines operated by different persons but also varies throughout a working day in a single machine when operated by the same person, this depending upon the fatigue of the operator.

In my invention the screw is operated automatically and the pressure of the tools upon the work is constant and the mechanism is so simple in its structure and assembling that it may be readily controlled and adjusted by a person with very limited mechanical knowledge and a single operator can with automatic feeding devices supervise the operation of a large number of grouped machines.

In the drawings, the numeral 1 designates the frame of the machine, 2 the gate, 3 the ways secured to the frame and in which the gate is slidably mounted, adjusting screw 4 being provided through the side of the frame to adjust the relative positions of the ways 3 and through it the friction upon the

gate 2. In practice, these ways 3 are adjusted so that the gate 2 moves quite freely therebetween.

On the frame at 5 one of the pair of working dies or punches is secured and the other one is secured in the gate at 6. These are brought together when the gate moves downwardly, and operate upon the work placed therebetween.

10 The mechanism above described constitutes no part of my present invention, as all of these elements have been heretofore combined in mechanism of this type and are old in the art.

15 The character of the work that can be operated upon, and the shape and structure of the dies and punches, can be and are varied indefinitely. In fact dies and tools of any structure can be mounted in this press, as in 20 those of the prior art.

25 Threaded through a boss 7 upon the top of the frame 1, is the operating screw 8, which has a rotatable connection with the gate 2 in a manner well known to the art and upon the upper end thereof is fixed a balance wheel 20.

30 The pitch of the thread on this screw is such that the gate will readily rebound when the tool in the gate hits the work to be operated upon. Secured upon the boss 7 by the set screw 10 is a retaining yoke 9, between the upper and lower arms of which is a collar 11 that is slidable upon the screw 8, but is prevented from rotation thereon 35 by the two keys 12, located diametrically opposite each other and slidable in keyways 13 in the screw 8. Between the collar 11 and the upper and lower arms of the retaining yoke 9, are the washers 14, which prevent endwise movement of the keys 12 in 40 relation to the collar 11.

45 On the collar 11 is a clamp arm 15, which is adjustably secured thereto by a friction block 16 which lies within the pocket 17 in said clamp arm 15 and is held against one side of the collar 11 by the adjusting screw 18 that is locked in its adjusted positions by a jam nut 19.

50 Fixed to the frame 1 is a bracket 21 having journaled therein a shaft 22, upon which is fixed a driving wheel 23 having connection by a belt or other means with any source of power, so that the shaft 22 is continuously driven in the direction of the arrow, shown in Fig. 2.

55 Adjacent to the upper end of the shaft 22 is fixed the friction housing 24, within which is fitted a hardened friction ring 25, which may be omitted if desired, although 60 I prefer to use it in most cases.

Rotatably mounted upon the upper end of the shaft 22 is a crank plate 26, upon the hub of which is mounted a friction disk 27 and held against rotation thereon by a plu-

65 rality of pins 28. By this construction the friction disk 27 and crank plate 26, when assembled, are a unitary structure, and held against endwise movement upon the shaft 22 by a cap 29 secured to the end of said shaft (see Fig. 2).

70 To reduce friction and make the clutch more sensitive, I prefer to provide a ball bearing 30 between the friction disk 27 and the housing 24. The friction disk 27 is provided with a plurality of peripheral notches 75 31, in the drawing three of such notches being shown, but the number may be varied if desired. Lying within each of these notches is a roll 32, which is mounted within a retaining saddle 33 pivotally secured to the friction disk 27 by the pin 34. A spring pin 35 having contact with the retaining saddle 33, mounted in the friction disk 27, is actuated by a spring 36, and has a tendency to push the roll 32 away from said pin 80 and in a direction parallel to that of the rotation of the housing 24.

85 In operation, shaft 22 and housing 24 are continuously rotated in the direction shown by the arrow in Figs. 2 and 8, and through 90 the frictional engagement of the rolls 32 with the inner face of the friction ring 25 and the long face of each of the notches 31 in the friction disk 27 rotation is also imparted to the disk 27 and crank plate 26. 95 If the rotary speed of the crank plate 26 is greater than that of the housing 24, the friction rolls 32 release their grip upon the inner face of the ring 25 and the disk 27 will move independently of the housing 24. 100 Rotation of the crank plate 26 and housing 24 as a unit is again obtained by reducing the speed of rotation of the friction disk 27, when the rolls 32 will again take up their frictional contact with the ring 25.

105 The numeral 37 designates the crank pin having a head 38 thereon that is slidably mounted in the groove 39 in a lug 40 upon the crank plate 26. Mounted upon the shank of this crank pin 37 is a bushing 41 110 that projects through a block 42 slidably mounted in the opening 43 in the crank arm 44 that is closed at one end by the cap 47. A collar 45 and a nut 46 hold the bushing and block just described against endwise 115 movement in relation to the crank plate, and provide means whereby the crank pin 37 may be held in any of its radial positions in relation to the center of the crank plate 26. The radial position of the crank pin 37 is 120 varied by means of an adjusting screw 52 threaded into the crank pin 37 and held against endwise movement by the lugs 53 upon the upper surface of the crank plate 26. The block 42 has a flexible connection 125 with the crank arm 44 through springs 48 upon either side thereof, one end of each of said springs being against said block and

the other end against the nuts 49 threadably mounted upon the fixed studs 50, one of these studs being fixed in the cap 47 and the other in the crank arm 44. The extent 5 of the flexibility may be varied by manipulation of the nuts 49 so as to vary the pressure of the spring upon the said block 42.

A pin 51 provides a pivotal connection between crank arm 44 and the clamp arm 15.

10 To operate the press the tools are arranged in a proper predetermined position. This is accomplished by adjusting the relative position of the gate 2 with the bed 5 and is secured by releasing the hold of the 15 friction block 16 upon the collar 11 and then rotating the screw through manipulation of the balance wheel 20 until the gate is in its correct position. The screw 18 is now manipulated forcing the friction block 16 against the bushing 11 and providing a 20 rigid connection between the clamp arm 15 and screw 8. The position of the gate above described is what is known as the down position, at which time the crank plate, crank 25 arm and clamp arm 15 are in substantially the relative positions shown in Fig. 3.

It being borne in mind that if nothing intervenes to prevent, the crank plate 26 rotates with the housing 24 in the direction 30 shown by the arrow in said figure, and from the point shown in Fig. 3, which may be considered for convenience of description, as the zero position, say for 180° or more, moves the clamp arm 15 from the position 35 shown in Fig. 3 to substantially that shown in Fig. 4, and during this rotation the screw is rotated through the collar 11 and keys 12, raising the gate to its up position, during all 40 of which time the friction rolls 32 are in contact with the ring 25. After the crank pin passes this point the crank arm pushes the clamp arm 15 back to the position shown in Fig. 3 for a number of degrees more or less, undetermined or until the linear velocity 45 of the pin 51 due to the momentum of the fly or balance wheel 20 becomes greater than the linear velocity of the crank pin 37. When this occurs the crank plate 26 will be drawn ahead of the driving shaft 22 and 50 friction housing 24, releasing the hold of the friction rolls 32 upon the ring 25, and the screw under the action of the momentum of the fly wheel 20 will run free and uninfluenced by the rotation of the shaft 22. 55 This continues until the blow of the tool in the gate upon the work causes the gate to rebound slightly. When this occurs the rotary action of the crank pin 37 is retarded slightly and the rolls 32 are again brought 60 into engagement with the inner surface of the ring 25 and the screw is returned through the rotation of the crank pin from the shaft 22. With this mechanism, with

the shaft 22 rotating at a constant velocity, the energy stored up in the fly wheel 20 will 65 always be the same and the blow struck on the work will not vary, as is the case with the hand driven screw press.

Within the limits of the appended claims, the details of the construction of my improved stamping press may be considerably altered and varied, and I would therefore have it understood that I do not limit myself to the construction herein shown and described but claim all that falls fairly 75 within the spirit and scope of my invention.

Having described my invention, what I claim as new and desire to secure by Letters Patent, is:—

1. The combination in a screw press; of a 80 driven element; a clutch; and means for automatically rotating the screw of said press in opposite directions from said driven element through said clutch.

2. In mechanism of the character de- 85 scribed, the combination with the screw; of a continuously rotating element; a make and break device interposed between said screw and rotating element; and a connection between said screw and make and break 90 device, said connection in part actuating said make and break device according to the direction of rotation and relative speed of said screw.

3. In mechanism of the character de- 95 scribed, the combination with the screw; of a continuously rotating element; and means for positively operating said screw in both directions from said rotating element, said means being in part controlled by the rela- 100 tive speed of said screw.

4. The combination in a screw press; of a driven element; a clutch means for automatically rotating the screw thereof in opposite directions from said driven element 105 through said clutch; and means whereby the point, when said screw changes its direction of movement, may be relatively varied.

5. The combination in a screw press; of a driven element; a clutch means for automatically rotating the screw thereof in opposite directions from said driven element through said clutch; means whereby the point, when said screw changes its direction of movement, may be relatively varied; and 110 means for varying the length of stroke of said screw.

6. In mechanism of the character de- 115 scribed, in combination with the screw; of a continuously rotating element; a connection having an operative engagement with said screw; and a make and break mechanism between said rotating element and said connection.

7. In mechanism of the character de- 125 scribed, in combination with the screw; of a

rotary element; a connection having an operative engagement with said screw; a make and break mechanism between said rotary element and said connection; and means for varying the relative point of engagement of said connection with said mechanism.

8. In mechanism of the character described, in combination with the screw; of a momentum member thereon; a continuously 10 rotating member; a connection between said screw and rotating member, whereby motion may be transmitted to said screw in both directions, such connection permitting said screw to run free under the impulse of 15 said momentum member.

9. In mechanism of the character described, in combination with the screw; of a mechanism for mechanically starting the rotation of said screw when in one of its 20 positions, then permitting the same to run free, and at the termination of its free run, mechanically rotating the same in the reverse direction, said free run and the starting of the mechanical rotation of the screw 25 in the said reverse direction being dependent in part upon the relative speed of rotation of said screw.

10. In mechanism of the character described, in combination with the screw; of a momentum device connected with said screw; mechanism for mechanically starting the rotation of said screw when in one of its 30 positions, then permitting the same to run free under the impulse of said momentum device, and at the termination of its free run, mechanically rotating the same in the reverse direction, said free run and the starting of the mechanical rotation of the screw 35 in the said reverse direction being dependent in part upon the relative speed of rotation of said screw.

11. In mechanism of the character described, the combination with the screw; of a rotary element; a connection between said 45 screw and rotary element, including means whereby said screw will acquire a speed greater than said rotary element; and means for operatively connecting said connection with said rotary element whereby its engagement therewith will be released under such increased speed.

12. In mechanism of the character described, the combination with the screw; of a rotary element; means for rotating the 55 same continuously in one direction; a connection having a permanent engagement with said screw and a make and break connection with said rotary element, the arrangement of said make and break connection being such that said screw is operated from said rotary element except when the speed of rotation thereof exceeds that of said rotary element.

13. In mechanism of the character described, the combination with a screw; of a

radial arm connected therewith; a continuously rotating member; a connection having a pivotal engagement with said arm; and a make and break mechanism between said connection and said rotating member. 70

14. In mechanism of the character described, the combination with a screw; of an arm connected therewith; means for securing said arm to said screw, so that its relative longitudinal position on said screw may 75 be varied; a continuously rotating member; a connection having a pivotal engagement with said arm; and a make and break mechanism between said connection and said rotating member.

15. In mechanism of the character described, the combination with a screw; of an arm connected therewith; a rotary member; a crank plate; a connection having an operative engagement with said arm; means 85 whereby said connection may have a flexible engagement with said crank plate; and a clutch mechanism having a separable operative engagement with said crank plate and rotary member. 90

16. In mechanism of the character described, the combination with a screw; of an arm connected therewith; a rotary member; a crank plate; a connection having an operative engagement with said arm; means 95 whereby said connection may have a flexible engagement with said crank plate; a clutch mechanism having a separable operative engagement with said crank plate and rotary member; and means for varying the relative position of the mechanism uniting said crank plate and connection. 100

17. In mechanism of the character described, the combination with a screw; of an arm connected therewith; means for adjustably securing said arm to said screw; a crank plate; a connection between said crank plate and arm having a flexible engagement with the former and a pivotal connection with the latter; a rotary member; and a 110 clutch between said crank plate and rotary member.

18. In mechanism of the character described, the combination with a screw; of an arm connected therewith; means for adjustably securing said arm to said screw; a crank plate; a connection between said crank plate and arm having a flexible engagement with the former and a pivotal connection with the latter; a rotary member; and a clutch between said crank plate and rotary member, the arrangement of such elements being such that the said clutch is operated in one direction by said rotary member and in the opposite direction through 125 said crank plate.

19. In mechanism of the character described, the combination with a screw; of a momentum member connected therewith; a rotating member continuously rotating in 130

the same direction; a crank plate; a clutch between said crank plate and rotary member, the action of which is in part controlled by the speed of rotation of said crank plate, 5 running free when rotating at a speed greater than said rotary member; and a connection between said screw and said crank plate.

20. In mechanism of the character described, the combination with a screw; of a continuously rotating element; a connection between said screw and rotating element, said connection comprising in part a make and break device so arranged and operated 10 that parts thereon engage with said rotary element when the latter is moving at a speed greater than that of said screw but said parts are disengaged therefrom when said screw is rotating at a speed greater than 15 20 said rotary element.

21. In mechanism of the character described, the combination with a screw; of an arm connected therewith; a rotary member; a connection having a pivotal engagement 25 with said arm; a make and break mechanism between said connection and said rotary member; and flexible elements between said connection and the rigid part on said crank plate.

30. 22. In mechanism of the character described, the combination with a screw; of an arm connected therewith; means for adjustably securing said arm to said screw; a crank plate; a connection between said 35 crank plate and arm having a flexible engagement with the former and a pivotal connection with the latter; a rotary member; a clutch between said crank plate and rotary member; and means for varying the 40 tension of said flexible engagement.

23. In mechanism of the character described, in combination with the screw; of a rotary element; a connection having an operative engagement with said screw; a crank 45 plate; a make and break connection between said crank plate and rotary element; a rigid element mounted on said crank plate; a tension mechanism joining said connection and rigid element; and means for varying the 50 tension of said tension mechanism.

24. In mechanism of the character described, in combination with the screw; of a rotary element; a connection having an operative engagement with said screw; a crank 55 plate; a make and break connection between said crank plate and rotary element; a crank pin on said plate; a tension mechanism joining said connection and crank pin, comprising

ing companion springs, one upon each side of said crank pin; and means for varying the tension of either or both of said springs. 60

25. In mechanism of the character described, in combination with the screw; of a rotary element; a connection having an operative engagement with said screw; a crank 65 plate; a make and break connection between said crank plate and rotary element; a crank pin on said plate; a tension mechanism joining said connection and crank pin, comprising companion springs, one upon each side 70 of said crank pin; means for varying the tension of either or both of said springs; and means for varying the relative position of said crank pin on said crank plate.

26. In mechanism of the character described, the combination with the screw; of a rotary element; means for rotating the same continuously in one direction; a connection having a permanent engagement 75 with said screw and a make and break connection with said rotary element, the arrangement of said make and break connection being such that said screw is operated from said rotary element except when the speed of rotation thereof exceeds that of 80 said rotary element and again restored when the said screw comes to a stop or its speed is equal to or less than that of said rotary element.

27. In mechanism of the character described, the combination with a screw; of a continuously rotating element; a rotatably mounted member; a movable part on said member arranged so that in one of its positions it forms a medium whereby a rigid 95 connection is made between said rotary element and said rotatably mounted member and both rotate in unison, and in another of its positions will break said connection so that said rotatably mounted member is free 100 and independent of said rotating element; and a connection between said rotatably mounted member and said screw.

28. In mechanism of the character described, the combination with a screw; of a momentum device thereon; a rotary member; and means for connecting said screw and rotary member so that said screw will be rotated by said rotary member until the speed of said screw exceeds that of said rotary member when it will be released from 105 said rotary member and run free.

In testimony whereof I have hereunto affixed my signature.

ZENAS P. CANDEE.
